UNITED STATES PATENT OFFICE

FREDERICK J. HOLMES, OF DETROIT, MICHIGAN, ASSIGNOR TO UNITED STATES TRUST COMPANY OF DETROIT, TRUSTEE, A CORPORATION

ROTARY VALVE

REISSUED

Application filed June 7, 1928. Serial No. 283,619.

This invention relates to a rotary valve designed primarily for use in connection with internal combustion engines, one of the objects of the invention being to combine, with a 5 rotary valve, a takeup device providing a sealed connection between the valve and the cylinder ports whereby loss of pressure is eliminated, the said takeup operating automatically to compensate for all wear between 10 the cooperating parts or any irregularities of contour.

A further object is to provide an automatic sealing connection of this type which will stand up under the intense heat to which 15 the parts are subjected while in operation.

A still further object is to employ a rotary valve for use in connection with the automatic sealing device, the construction of the valve being such that it will be automatically 20 cooled by the fuel being supplied to the engine, this fuel, in turn, being maintained in a highly vaporized state by the heat from the exhaust gases.

A further object is to provide an improved 25 sealing means on the valve for cooperation with the port sealing means whereby loss of pressure between the valve and its casing is prevented and lubricant is excluded from the interior of the valve and from the ports of 30 the cylinders with which the valve cooperates.

A further object is to provide a rotary valve which, by reason of its peculiar construction and the parts associated therewith, will not warp in operation but will maintain 35 a high degree of efficiency under all working conditions, and irrespective of any expansion or contraction of the working parts.

With the foregoing and other objects in view which will appear as the description 40 proceeds the invention resides in the combination and arrangement of parts and in the details of construction hereinafter described and claimed it being understood that changes in the precise embodiment of the invention herein disclosed may be made with-

in the scope of what is claimed without departing from the spirit of the invention.

In the accompanying drawings the preferred forms of the invention have been shown.

In said drawings,

Figure 1 is a longitudinal section through a portion of the head of the engine, portions of cylinders cooperating therewith being also shown in section and a valve in the head being shown partly in section and partly in elevation.

Figure 2 is a section on line 2—2, Figure 1.

Figure 3 is a section on line 3—3, Figure 2.

Figure 4 is a section on line 4—4, Figure 2.

Figure 5 is a section on line 5—5, Figure 1.

Figure 6 is a perspective view of one of the sealing sleeves of the valve.

Figure 7 is a perspective view of one of the port takeups or sealing blocks.

Figure 8 is a perspective view of the support and guide for the block shown in Figure 7.

Figure 9 is a view similar to Figure 2 showing a slightly modified construction.

Figure 10 is a perspective view of the modified form of sealing block or takeup shown in Figure 9.

Figure 11 is a perspective view of the port and guide therefor.

Figure 12 is a side elevation of the takeup block and guide assembled.

Referring to the figures by characters of reference 1 designates the cylinder block of an engine on which is suitably secured the head 2 which, as shown particularly in Figure 5, is provided with a cylindrical valve casing 3 surrounded preferably by a water jacket 4 to which access can be had through an opening 5 normally closed by a removable plate 6. A port 7 extends throughout the valve casing 3 so as to open through the head into the adjacent cylinder, it being understood that one of these ports is provided for each cylinder.

Located in each cylinder and secured tightly against the head 2 is a flange 8 extending around and integral with one end of a guide sleeve 9 which is extended into the port 7 but spaced from the wall thereof. This sleeve is preferably angular as shown particularly in Figure 8 and is surrounded by a takeup member or block 10 adapted to reciprocate in the space between the wall of the port 7 and the sleeve 9. This block has one end portion lapping the end of the sleeve 9 as shown at 11 and the opening 12 through the end portion of the block is of the same size and proportion as the passage within the sleeve 9. In the structures illustrated in Figures 1 to 8 inclusive a seal ring 13 extends around and is seated within the member 10 where it will tightly engage that end portion of the wall of the port 7 remote from the cylinder. Another seal ring 14 extends around and is carried by the guide sleeve 9 near that end thereof remote from the flange 8 and this ring is adapted to fit firmly and tightly against the inner surface of the member 10. Member 10 does not extend downwardly to the flange 8. Instead a space 15 is left between said flange and the adjacent end of the member 10, this space providing a sealing chamber for holding oil adapted to be supplied to said chamber or pocket from the force feed lubricating system of the engine through a bore 16 extending from a feed pipe 17 as shown in Figure 2. That end portion of the member 10 remote from the flange 8 constitutes the head or bearing portion of the takeup and is concaved transversely as indicated at 18 in Figure 7 so as to fit snugly against the periphery of the valve hereinafter described. Recesses or apertures 19 are formed in the opposite edge portions of the concave surface 18 and are provided for the purpose hereinafter explained. Springs 20 are housed in the pocket 15 and bear against flange 8 and also against the adjacent end of the member 10. These springs are constantly submerged in the oil in the pocket 15 so as to be kept cool thereby. They also serve to hold the concave head of the member 10 pressed constantly against the valve 50 of the engine.

Mounted for rotation within the housing 3 in head 2 is a cylindrical rotary valve 21 having a concentric tubular core 22 constituting the exhaust manifold of the engine. This core or exhaust manifold is spaced from the peripheral portions of the rotary valve and, as shown at the right of Figure 1, can be extended beyond the head 2 where a suitable bearing 23 can be employed for facilitating rotation of the valve. An annular groove 24 is formed in the outer surface of the valve opposite each of the ports 7 and the concave face 18 of each of the takeup members 10 is adapted to bear against the valve within each of these grooves 24, the said takeup

member being of a length substantially equal to the width of the groove in which it is seated. Extending to the exhaust manifold 22 from each of the grooves 24 is an exhaust port 25 and formed in the valve at proper points are intake ports 26 adapted to register with the openings 12 at the proper times during the cycle of operation of the engine. As shown particularly in Figure 2 the exhaust port 25 extends through slightly less than ninety degrees. The intake port associated with said exhaust port 25 and indicated at 26 extends through substantially ninety degrees but the advancing wall of this port, indicated at 27, has a cutoff flange 28 extending therefrom for the purpose of maintaining the opening 12 completely closed until the exhaust port 25 has passed out of communication with said opening. The remaining space within the valve outside of the exhaust manifold 22 and between exhaust port 26 and the exhaust port 25 provides an intake manifold 29 into which fuel will be directed from the supply port of the engine.

The ports 25 and 26 are arranged preferably in pairs, one port 25 and one port 26 being provided for each of the ports 7 and the same being so located as to operate in properly timed relation. Arranged between these pairs of ports is a fuel supply port 30 shown particularly in Figure 5. This fuel supply port is closed at its outer end by an annular flange 31 carried by a guide sleeve 32 similar to the sleeve 9 and providing an oil pocket 33 around the sleeve and within the port 30. A takeup block 34 similar to the block 10 extends around the sleeve 32 and within port 30 and is provided with a seal ring 35. A seal ring 36 is also carried by the sleeve 32. The head portion 37 of the takeup block is similar to the head portion of the block 10 already explained and is adapted to be held against the periphery of the rotary valve 21 by springs 38 seated in the oil pocket. A fuel supply pipe 39 opens into the sleeve 32 and as the oil pocket 33 is in communication through a bore 40 with a pipe 41 of the pressure lubricating system, it will be apparent that the springs will be constantly submerged and thus protected from injury by heat. The head of the block 34 engages within an annular groove 42 formed in the outer periphery of the valve 21 between the grooves 24 and, as shown particularly in Figure 5, a port 43 is formed in the valve 21 and extends through approximately two hundred seventy degrees so as to maintain communication between the intake manifold 29 and the fuel inlet while the ports 26 are in communication with the respective cylinders.

For the purpose of maintaining a sealed connection between the rotary valve and its casing irrespective of any contraction or expansion of the parts that might take place, there is provided within each of the grooves

24 and 42 a sealing sleeve 44 shown in detail in Figure 6. This sleeve is preferably formed of three arcuate resilient plates 45, 46, and 47. Plate 45 is provided at the sides of each end with recesses 48 in the outer surface thereof and extending from the ends of the plate between these recesses are tongues 49 the outer faces of which are cut away as shown at 50. Cooperating with each end of the plate 45 are the adjacent ends of the plates 46 and 47. Each of these plates has tongues 51 extending from the sides thereof at its end, the tongues being cut away at their inner sides as shown at 52 so as thus to form a sliding lapping contact with the plate 45 within the recesses 48. The ends of the plates 46 and 47 nearest plate 45 have their inner faces cut away between the tongues 51 as shown at 53 to receive the tongues 49 which thus have a sliding lapping contact. As the tongues 49 have their outer faces cut away, transverse shoulders 54 are produced between the base portions of the tongues 51. These shoulders 54 cooperate with the shoulders 50 to form pockets 55 in which springs 56 are seated. These springs are adapted normally to hold the plates 46 and 47 pressed away from the plate 45 without, however, breaking the lapping contact between the cooperating portions of the plates.

Those ends of the plates 46 and 47 remote from the plate 45 are formed with transverse tongues 57 terminating inwardly from the opposed edges of the plates as shown particularly in Figure 6. These tongues are adapted to fit snugly within the grooves 19 in the adjacent takeup member or block 10 as is illustrated more especially in Figure 3.

It is to be understood that the band or sleeve 44 is proportioned to fit snugly against the periphery of the valve within that groove in which the band or sleeve is mounted. For the purpose of holding said band or sleeve spaced from the inner surface of the valve casing or housing 3 a spring 58 in the form of a transversely corrugated strip is seated within the groove and outside of the sealing band or sleeve, the ends of this spring terminating at opposite sides of the adjacent takeup member 10 or 34. These springs tend constantly to contract the sealing band 44 about the sleeve so as to provide a tight connection which will compensate for wear and any irregularities of contour. As before explained one of the sealing bands or sleeves 44 is located within each of the grooves in the valve and one of the springs 58 is located around each of these bands or sleeves. Lubricant is supplied to the spaces occupied by the springs 58 from a bore 59 communicating with the force feed lubricating system, this bore having outlets 60 opening into the several spaces occupied by the springs 58.

As before explained the springs 20 and 38 are constantly submerged in oil. These

springs serve to hold their respective takeup blocks pressed against the periphery of the valve so as to provide a tight connection through which pressure cannot leak. As oil under pressure is located back of the respective takeup blocks or members, this oil will act to press against said members and force them firmly against the valve. The springs are merely employed for holding the members in active positions. The oil acts to provide the necessary seal to prevent leakage. The oil also serves to prevent the springs from being burned or otherwise injured from excessive heat in the engine. The sealing bands or sleeves provide tight connections between the valve and the ends of the takeup members 10 and 34 and also constitute contractile inner casings for the valve so as to prevent leakage of pressure along the valve in any direction. As the valve rotates in properly timed relation to the reciprocation of the pistons of the engine the ports 26 will be brought into communication with the openings 12 in the members 10, thereby to supply fuel to the cylinders during the intake stroke. Likewise, at the proper time during the cycle of operation, the exhaust port 25 will be brought into communication with the opening 12 in the adjacent takeup member 10. The gases will be exhausted into the manifold 22 and will serve to maintain the highly vaporized condition of the gas in the intake manifold 29. This vaporized gas will prevent direct conduction of heat from the manifold 22 to the periphery of the valve. The periphery of the valve will be kept cool by the gas between the manifold 22 and said periphery with the result that expansion and contraction will be reduced to the minimum. However, any such expansion or contraction which may occur will be compensated for by the relatively movable sealing members indicated at 44, 34, and 10.

Aside from their function as a means for forming a tight seal about the rotary valve, the bands or sleeves 44 also serve to prevent oil from leaking into the cylinder ports from about the valve.

While it is preferred to depend on oil under pressure as a means for holding the takeup members pressed against the periphery of the valve, thereby to supplement the action of the springs, it is to be understood that, if preferred, a structure such as illustrated in Figure 9 may be utilized. In this structure the ring 14 is dispensed with. Instead the guide member 61 which forms the oil pocket 62 within port 63 receives the takeup member 64 which has a seal ring 65 extending therearound in sliding contact with the wall of the port 53. During the operation of the engine pressure from the cylinder will be exerted over the end of the guide member 61 and back against the oil in the pocket 62 thereby forcing said oil to press against mem-

ber 64 which, consequently, will be held with proper pressure against the periphery of the cylindrical valve.

Under some conditions it might be possible 5 to dispense with a pressure lubricating system altogether and to rely solely on the action of springs 66 against the takeup member 67 as shown in Figure 12. It will be necessary, however, to have these springs submerged in 10 oil as otherwise they would be soon rendered inefficient.

What is claimed is:

1. In an internal combustion engine the combination with a cylinder block, a head 15 thereon having an interior valve casing, there being a port extending from the interior of the cylinder block into the valve casing, of a rotary valve within the casing, a guide member within and spaced from the walls of the 20 port, a takeup member slidable upon the guide member and within the port, there being a lubricant pocket around the guide member and back of the takeup member, and resilient means normally submerged in lubricant 25 within the pocket for holding the takeup member pressed against the periphery of the valve, said takeup member having an opening for communication with the ports in the valve and with the port in the head.

30 2. In an internal combustion engine the combination with a head having a valve casing, therein, and a port leading from said casing through one wall of the head for communication with a cylinder, of a valve mounted 35 for rotation in the casing having fuel and exhaust ports for alternate communication with the port in the head, a guide member within the port in the head, a takeup block extending therearound and slidable within 40 said port, means for exerting constant pressure against one end of the takeup block for holding the other end thereof constantly in sealing and working contact with the periphery of the valve, and a contractible sealing 45 member interposed between the valve and its casing and abutting at its ends against the takeup block.

3. The combination with the head of an 50 internal combustion engine having a valve casing therein and a port extending from said casing through one wall of the head for communication with a cylinder, of a rotary valve within the casing having separate fuel and exhaust ports for successive communication with the port in the head and 55 casing, a guide member within and spaced from the walls of the port in the head, a takeup block extending therearound and slidable thereon, yielding means for holding 60 said block in sealing and working contact with the periphery of the valve, said valve having an annular groove into which the takeup block projects, means for subjecting the takeup block to end pressure for holding 65 the same in sealing contact with the grooved

valve, a contractible and expansible sealing band within the groove abutting at its ends against and held against rotation by the takeup block, and resilient means for holding 70 said band pressed against the valve.

4. The combination with the head of an internal combustion engine having a cylindrical valve casing therein provided with a port extending through the wall of the head for communication with a cylinder, of a takeup block slidably mounted in said port, a rotary valve in the casing having separate fuel and exhaust ports for successive communication with the ports in the block, means 80 for maintaining a pressure against the takeup block for holding it in sealing and working contact with the periphery of the valve, a sectional sealing band extending around the valve and abutting at its ends against the takeup block, resilient spreading elements 85 interposed between the ends of the sections of the band, a resilient means engaging the band and bearing against the valve casing for holding said band contracted upon the valve to maintain a sealed working fit between the band and the valve, and means for directing lubricant into the space between said band and the valve casing.

5. In an internal combustion engine a head having a cylindrical valve casing therein, there being a port extending from said casing through one wall of the head for communication with the interior of a cylinder, a valve mounted for rotation within the casing having non-communicating concentric intake and exhaust manifolds therein, there being a port within the valve communicating with the respective manifolds and movable into successive communication with the port in the head, there being an annular groove in the outer surface of the valve from which the ports extend, a resiliently held takeup block slidable in the port in the head and casing and having a sealing working fit against the periphery of the valve and within the groove, an extensible sealing band including lapping sections 100 extending around the valve within the groove and abutting at its ends against the takeup block, and means between the valve casing and the band for holding said band contracted about the valve to maintain a sealing fit between said valve and the band.

6. In an internal combustion engine a head having a valve casing therein, there being a port extending from said casing through one wall of the head for communication with a cylinder and another port extending from said casing through one wall of the head for communication with a fuel supply, a rotary valve within the casing having annular grooves, takeup blocks within the ports, means for subjecting said blocks to pressure for maintaining a sealing working connection between the blocks and the grooved portions of the valve, there being concentric 110 115 120 125 130

intake and exhaust manifolds within the valve, there being a port in the intake manifold portion of the valve for communication with the intake port and separate ports in the intake and exhaust manifold portions of the valve for successive communication with the port leading to the cylinder, and extensible, contractible, sealing bands within the respective grooves providing sealing working connections between the valve and its casing, the ends of the bands abutting against and being held against rotation by the takeup blocks.

7. In an internal combustion engine the combination with a head having a valve casing therein and a port leading from said casing through one wall of the head for communication with a cylinder, of a valve mounted for rotation in the casing having fuel and exhaust ports for alternate communication with the port in the head, a guide member detachably secured to one face of the head whereby, when the head is removed from its cylinder, said end of the member and its fastening means are exposed, said guide member being extended into the port in the head, a takeup block extending around the guide member and slidable within the port, and means for exerting constant pressure against one end of the takeup block for holding the other end thereof constantly in sealing and working contact with the periphery of the valve, said takeup block being removable with the guide member from the port.

8. In an internal combustion engine the combination with a head having a valve casing therein and a port leading from said casing through one wall of the head for communicating with a cylinder, of a valve mounted for rotation in the casing having fuel and exhaust ports for alternate communication with the port in the head, a guide member detachably secured to one face of the head whereby, when the head is removed from its cylinder, said end of the member and its fastening means are exposed, said guide member being extended into the port in the head, a takeup block extending around the guide member and slidable within the port, and means for directing a lubricant under pressure against one end of the takeup block thereby to hold the other end thereof constantly in sealing and working contact with the periphery of the valve.

9. In an internal combustion engine the combination with a head having a valve casing therein, and a port leading from said casing through one wall of the head for communication with a cylinder, of a valve mounted for rotation in the casing having fuel and exhaust ports for alternate communication with the port in the head, a guide member within the port in the head, a takeup block extending therearound and slidable within said port, means for exerting constant pressure against one end of the takeup block for

holding the other end thereof constantly in sealing and working contact with the periphery of the valve, and a contractible sealing member interposed between the valve and its casing, said takeup block constituting means for holding the sealing member against rotation with the valve.

10. The combination with the head of an internal combustion engine having a valve casing therein and a port extending from said casing through one wall of the head for communication with a cylinder, of a rotary valve within the casing having separate fuel and exhaust ports for successive communication with the port in the head and casing, a guide member within and spaced from the walls of the port in the head, a takeup block extending therearound and slidable thereon, yielding means for holding said block in sealing and working contact with the periphery of the valve, means for subjecting the takeup block to end pressure for holding the same in sealing contact with the valve, a contractible and expandible sealing band held against rotation by the takeup block, and resilient means for holding said band pressed against the valve.

11. The combination with the head of an internal combustion engine having a cylindrical valve casing therein provided with a port extending through the wall of the head for communication with a cylinder, of a takeup block slidably mounted in said port, a rotary valve in the casing having separate fuel and exhaust ports for successive communication with the ports in the block, means for maintaining a pressure against the takeup block for holding it in sealing and working contact with the periphery of the valve, a sealing band extending around the valve held against rotation by the takeup block, resilient spreading elements interposed between the ends of the sections of the band, a resilient means engaging the band and bearing against the valve casing for holding said band contracted upon the valve to maintain a sealed working fit between the band and the valve, and means for directing lubricant into the space between said band and the valve casing.

12. In an internal combustion engine a head having a valve casing therein, there being a port extending from said casing through one wall of the head for communication with a fuel supply, a rotary valve within the casing, takeup blocks within the ports, means for subjecting said blocks to pressure for maintaining a sealing working connection between the blocks and the valve, there being concentric intake and exhaust manifolds within the valve, there being a port in the intake manifold portion of the valve for communication with the intake port and separate ports in the intake and exhaust

manifold portions of the valve for successive communication with the port leading to the cylinder, and extensible, contractible, sealing bands providing sealing working connections between the valve and its casing, the bands being held against rotation by the takeup blocks.

In testimony that I claim the foregoing as my own, I have hereto affixed my signature.

10**FREDERICK J. HOLMES.****15****20****25****30****35****40****45****50****55****60****65**
